UNITED STATES PATENT OFFICE.

ARMAND PAILLONCY, OF CHENECIERE, FRANCE.

PROCESS FOR THE MANUFACTURE OF TOOLS OR IMPLEMENTS.

Application filed June 12, 1924. Serial No. 719,628.

To all whom it may concern:

Be it known that I, ARMAND PAILLONCY, a citizen of the Republic of France, residing at Cheneciere, Cote d'Or, France, have invented a certain new and useful Improved Process for the Manufacture of Tools or Implements, of which the following is a specification.

This invention relates to a process for the manufacture of tools or implements whose handles are inserted in closed sockets. It allows stronger and lighter tools to be obtained at a much lower cost.

Hitherto the process usually adopted consists of soldering a cut piece which necessitates forging, moulding and polishing, and produces tools which are rather heavy for their size.

In the process forming the subject of the present invention, the blank, after two simple operations and after rolling, is ready for stamping which takes place in a single operation.

A slight polishing is sufficient to obtain the finest polish. Moreover, through the possibility of using hard steels, the tools can be made considerably lighter, while increasing their strength.

The process will be explained with reference to the accompanying drawing which shows the parts formed in the various operations.

Figure 1 represents a composite view in plan, section and side elevation of a perforated blank or mass of metal illustrating the initial step of the process invention of this application.

Figure 2 is a side elevation of the mass after it has been rolled, subsequent to piercing;

Figure 3 is a plan view of the body of metal as shown in Figure 2;

Figure 4 is a plan and sectional view of the blank shown in Figure 3 after the blank has been trimmed;

Figure 5 is a plan view of one of the tools when cut to proper size from the blank shown in Figure 4; and

Figure 6 is a plan and sectional view of the tool after it has been finally rolled from its form shown in Fig. 5.

A. The primary mass of metal is of a size such that after the first rolling the sheet will give in length two blanks, and in width as many as the roller mill will take. The heated blank is at its exit from the furnace put

under a press to make it absolutely straight. It is then delivered to a pressing machine where it is supported by a vice, and provided exactly at the centre of its thickness with as many recesses T as there are tools to be made. The sizes of these recesses and their respective positions will vary in accordance with the size of the tools.

After the recesses T have been made, the blank is again placed under the press which closes the lips formed when making the recesses (Figure 2), in order to allow the blank to be placed between the rolls of the rolling mill.

Rolling is at once effected by ordinary processes for forming a plate whose thickness corresponds to the maximum thickness which the finished blank may have, Figure 3.

The machines employed and the method of working are such that the metal does not require to be reheated between these operations.

B. The plate is trimmed at the two ends at m n and o p and then delivered to a press for inserting tools into the sheet at each place where the preliminary piercing of the blank has formed an opening. The operation allows the exact positions of the perforations to be seen at the outer surface of the blank and in accordance therewith the plate is cut in a guillotine into as many pieces as there are to be tools, Figure 4.

Each of such rectangular pieces is then cut by a press to the shape of the handle, whereby this may be exactly centred with respect to the hole pierces in the piece.

A portion of Figure 4 shows the cut to be effected for one tool, while a cut out tool with its stalk E is shown in Figure 5.

C. The cut pieces are then heated in a furnace to a low temperature for the purpose of avoiding oxidation, and rolled by a train of eccentric rollers to obtain a profile of a thickness decreasing from the shoulders to the cutting portion, and if necessary from the shoulders to the end of the stalk. The piece is thus given its final length; the cutting being effected with reference to the already cut stalk E Figure 6.

The blank is, by these two rolling operations, given the thickness necessary for the finished tool, and the desired position of stalk E and hole T for allowing the socket to be rimmed to receive the handle. The rimming of the socket, the stamping to the final

shape, as well as the tempering, may be effected with a single reheating and at one operation. Finishing is effected by a slight polishing for whitening the surface and giving it its final appearance.

Having now particularly described and ascertained the nature of my said invention and in what manner the same is to be performed, I declare that what I claim is:—

10 The process of manufacturing tools which consists in first heating a mass of metal, piercing the mass at opposite sides to provide opposed aligned openings for forming sockets, then rolling the mass into plate form

in a direction longitudinal to lines passing 15 through said aligned openings, cutting the plate into as many blanks as there are to be tools and in each of which the part which will form the socket is centered with respect to the opening therein, cutting from each blank a tool of substantially the approximate shape desired with a tang extending within the limits of the edges of the opening, and finally reheating and rolling the cut out piece to correct size.

20 25 In testimony whereof I affix my signature.

PAILLONCY, ARMAND.
